IMPREGNATED FIBROUS ARTICLE

Henry Ward Baldwin, Saegertown, Pa., assignor
to Baldwin Laboratories, Inc., Saegertown, Pa.,
a corporation of Pennsylvania

Application August 10, 1935, Serial No. 35,685

2 Claims. (Cl. 299—24)

This invention relates to manufacture of impregnated articles; and it comprises an article of fibrous material having a uniform texture containing absorbed therein spaced parallel tracks of a volatile liquid, such as perfume, the volatile liquid tracks substantially penetrating said absorbent material and the spaces between said tracks containing substantially less of said volatile liquid than said tracks; all as more fully 5 hereinafter set forth and as claimed.

In the prior art, the impregnation of paper and similar materials by liquids has been effected usually by spraying the liquid onto the material to be impregnated, according to any of the known 10 spraying methods, most frequently by hand; or by dipping the material into the liquid. These modes of procedure, however, involve numerous disadvantages. The dipping method is quite non-commercial, since it uses by far too large an 15 amount of material and often tends to damage the material treated. As to the spraying method, in order to obtain a uniform distribution, the liquid is sprayed over the entire surface of the material to be impregnated, which results in a 20 large amount of liquid being used unnecessarily. The liquid does not penetrate the material unless an excessive amount is employed and is quickly dissipated by volatilization. The method 25 is slow and the impregnation is not uniform. The spraying method also constitutes a fire hazard, since a cloud of a highly volatile and inflammable material is produced.

The articles of the present invention are impregnated in the form of more or less narrow liquid tracks which penetrate the absorbent material and from which the fluid gradually tends to permeate the entire material. This results in a 30 minimum loss by volatilization, an economical use of the liquid, and it eliminates the hazard of fire 35 encountered in the spraying method.

While various methods may be used to produce impregnation of the articles of the present invention, one impregnating machine, which I have found very useful, will be briefly described. 40 In this machine a set of three rolls, advantageously driven from a common drive, is provided in which the top and bottom rolls are made with a continuous surface while the middle roll is arranged in sections. Each of these sections comprises an annular ring of absorbent material, such as felt, clamped between metal portions. These 45 annular rings, which have a slightly greater diameter than the metal portions, come in contact with both the top and bottom rolls. The bottom 50 roll is partly submerged in a tank containing the

impregnating liquid, and when rotated feeds the liquid to that portion of the felt rings in contact therewith. The material to be impregnated is fed between the top roll and the upper portion of the felt rings, which when rotated, transfer 5 the liquid absorbed from the bottom roll to the material to be impregnated.

The individual sections of the center roll are spaced according to the distance desired between the liquid tracks on the material, and the portions of the felt rings protruding above the surfaces of the holding members are adjustable. It is also possible, of course, to employ felt rings of varying widths. By these means the amount of liquid conveyed to the material to be impregnated 10 can be readily predetermined and waste of the impregnating liquid is substantially eliminated.

My invention is illustrated in the accompanying drawing which represents a perspective view of a sheet of absorbent material impregnated 20 with spaced parallel tracks of a volatile liquid which loses its value upon volatilization, part of this view being a longitudinal section through said sheet. The thickness of the sheet is exaggerated in order to show the impregnating liquid 25 more clearly. In this showing the impregnating liquid is shown in dotted lines, the density of impregnation being indicated by the spacing of these lines. The legends of the drawing are believed to make the drawing itself explanatory. 30 The longitudinal section is taken through one of the tracks of volatile liquid.

My invention has many obvious advantages. I have found, for example, that when impregnation is accomplished in the form of spaced liquid 35 tracks, the loss by volatilization is much less than when the impregnation is uniform. I attribute this to the fact that the liquid surface exposed to the air is greatly reduced. In one case the resulting relatively thick strips of liquid present a 40 small surface of exposure while in the other case the whole surface area is impregnated and exposed to loss by volatilization. In particular I have found that blotters impregnated with perfume by my method retain their odor several 45 times as long as similar blotters which have had their surfaces uniformly impregnated with the same amount of perfume. It is therefore evident that the present invention affords a substantial saving both in cost of impregnating materials as 50 well as in labor.

One of the most advantageous embodiments of my invention is a blotter impregnated with perfumes for advertising purposes. I usually impregnate large sheets of blotting paper and then 55

cut these sheets up in such manner as to obtain a single fluid track across each blotter. In this manner an important saving in impregnating material is realized but, on account of the particular manner in which impregnation is accomplished, the blotters retain the aroma of the perfume for a long period of time.

Any type of manufactured, fibrous absorbent material can be used in making the articles of the present invention, for example textile materials, paper, leather and the like. And these articles can be impregnated with various types of liquids losing their value upon volatilization. The machine described briefly above may be adapted to impregnate irregularly shaped articles by suitable shaping of the rolls and by providing flexible felt strips of considerable width, hence my invention is not limited to articles of sheet material.

Other modifications which fall within the scope

of the following claims will be immediately evident to those skilled in the art.

What I claim is:

1. As a new article of manufacture, a manufactured, fibrous, absorbent material having a uniform texture containing absorbed therein spaced parallel tracks of a volatile liquid losing its value upon volatilization, the volatile liquid tracks substantially penetrating said absorbent material and the spaces between said tracks containing substantially less of said volatile liquid than said tracks. 5

2. A perfumed blotter containing absorbed therein spaced parallel tracks of perfume, the perfume in said tracks substantially penetrating said blotter and the spaces between said perfumed tracks containing substantially less perfume than said tracks. 10 15
